UNITED STATES PATENT OFFICE.

ANNA V. CASSITY, OF OKMULGEE, OKLAHOMA.

NURSERY-CABINET.

1,027,816.

Specification of Letters Patent.

Patented May 28, 1912.

Application filed June 16, 1911. Serial No. 633,543.

To all whom it may concern:

Be it known that I, ANNA V. CASSITY, a citizen of the United States, residing at Okmulgee, in the county of Okmulgee and State of Oklahoma, have invented a new and useful Nursery-Cabinet, of which the following is a specification.

This invention relates to cabinets and has for its object the provision of a compact structure which can be used as a wardrobe and also has facilities for keeping food, medicine, damp and soiled clothes, toilet accessories, etc.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings, the preferred form of the invention has been shown.

In said drawings:—Figure 1 is a front elevation of the closed cabinet. Fig. 2 is a side elevation thereof. Fig. 3 is a cross section on the line 3—3 of Fig. 1. Fig. 4 is a front elevation of the cabinet open. Fig. 5 is a cross section on the line 5—5 of Fig. 4. Fig. 6 is a plan view illustrating the cabinet partly open so as to protect a child from draft. Fig. 7 is a detail view of an auxiliary extinguisher for use with the lamp. Fig. 8 is a detail view of a utensil support which may be used in connection with the lamp.

The cabinet is made in three sections as best seen in Figs. 5 and 6, the intermediate or larger section A constituting the body and the two smaller roller supported side sections B and C constituting doors hinged to the body as at D so as to close the front thereof when they are folded together. These doors may be extended laterally as shown in Fig. 5, so that one of them can be used as a wardrobe and the other as a closet. By moving the doors to the positions shown in Fig. 6, they can also be used as a screen to protect a child from drafts while it is being bathed or clothed.

The body member A has a lid 5 (see Fig. 2) hinged as at 6 so as to close an opening in the top of the case, and this lid may have a mirror 7 on its under side to be used when the lid is raised. This lid closes the top of

a compartment 8 in the upper portion of the body A, the bottom of the compartment being a transverse shelf 9 upon which may be laid long garments which it is not desired to fold, and upright rods 10 extend across the front of the compartment at its ends so that the garments therein may be viewed but cannot fall out. Compartment 8 is located rather high in the cabinet, because one can see into it even as so placed; but the drawers 11 and 12 which are to be used like those in an ordinary bureau, dresser, or chiffonnier I place a little lower where one while seated can look into them when they are drawn out. Between these drawers and the shelf 9 is a space (best seen in Fig. 3) in which are disposed a number of rods 13 for supporting damp towels or other articles, and by preference I arrange these rods in two groups of four in each group, and insert the rods of one group through one end of the body and the rods of the other through the other end of the body, all of the rods being thus disposed in staggered relation. By this arrangement certain of the rods can be drawn out by means of small rings 13' when it is desired to have a more open space, and all of them can be drawn out at any time for cleansing or repairing them. Beneath the space which receives the drawers 11 and 12, is an upright partition 15, leaving a space 16 at the left in which may be stored diapers and the like and a space 17 at the right which we call the lavatory.

18 designates a pitcher which may be placed in the lavatory, and 19 is the basin removably mounted within a bracket 20 which is supported and adapted to swing in eyes 21 so that the entire basin can be shifted out into position for use as seen in Figs. 5 and 6 or can be moved back into and housed within the cabinet when not to be used. I find this space 17 also convenient for storing a lamp (alcohol or the like) 22 which also may be mounted in a swinging bracket 20 pivoted in eyes 21. An auxiliary lamp extinguisher 23 may also be mounted in the space 17 and consists of a plate 24 hinged or linked as at 25 to an arm 26 which has a fixed support 27 at its remote end, the length of the arm and the position of the hinges of the plate being such that the latter will engage the lamp burner and extinguish the flame when the lamp is swung back into space 17. Obviously if the lamp is lighted and left beneath the basin the water in the

latter will be heated, or the lamp can be lighted and swung outward for the purpose of heating other articles as may be necessary. A shelf 28 forms the bottom of the compartments or spaces 16 and 17, and the space below this shelf may be divided by upright partitions 29 into a central space for a fireless cooker 30; a left hand space 31 having a drawer 32 in the upper portion thereof said space being adapted to receive a nursery chair; and a large right hand space 33 for soiled clothes. A slat 34 is extended across the front of space 33 to prevent the clothes from falling out.

15 The left hand door member B which may be called the closet, is not as deep as the body member A although it is of the same height, and preferably half the width of the body member. If the cabinet is sufficiently wide, a series of shelves 40 can be arranged down one edge of each door member, each shelf having a rod 41 across it to retain upon the shelf any articles that may be stored thereon. In smaller cabinets, these 20 series of shelves may be omitted. In either event, however, the upper end of this member B is preferably formed into a compartment 42 for storage of a hot water bag 43, a syringe, a sponge, and other articles which 25 are moist and which might drip. In fact, I prefer to form the bottom of this compartment in the shape of a pan 44 having a sloping bottom 45 leading downward to a drain 46 which delivers into a vessel 47. In 30 this pan may be placed a wet sponge or syringe or other article, although the compartment 42 will be sufficiently deep to store many such articles in it. Below the pan 44 is a space 48 of sufficient size to receive a child. At the lower end of this space is a 35 seat 49 hinged as at 50 to a cross strip 51 which is fixed to the back of member B. A guard 52 leads downward from the front portion of the seat to the vessel 47 as shown.

40 When the seat is let down into place it rests upon strips 53, but when it is raised it will rest against the back of member B. Strap 54 is to be used for holding a child upon the seat. The compartment 42 can be provided 45 with a door, if desired, but the space 48 should not be closed because it is to be used as a closet as explained. The vessel 47 rests upon a shelf 55 secured rigidly within the lower end of the compartment B but projecting beyond its open face, and when this member is folded against the body member A the shelf passes into the space 31 in the latter.

50 The right hand member or door section C 55 of this cabinet is preferably about the same

size and shape as the member B, and may be called the wardrobe section because the greater portion thereof is devoted to the storage of clothes which can be hung on hooks 60 as seen in Fig. 4. This wardrobe 65 is provided with a hinged door 61 as shown in Fig. 1 and which would stand at the rear when the device is opened wide as shown in Fig. 4. The back of the wardrobe which appears in front of the cabinet when extended (see Fig. 4) may be provided with a mirror 62 or paneled as shown at 63 for ornamentation. Projecting rigidly from this face of this member is a stout thin shelf 64 which serves as a table when the cabinet 70 is used as seen in Fig. 6. This table passes over the basin 19 when this member C is closed upon the member A. If the shelves and compartments elsewhere contained in this cabinet as described above are not sufficient for medicines, the upper portion of this member C may be devoted thereto, and has shelves 65 provided with rods 66 to prevent bottles from falling off when this member is moved over the floor. The whole 75 compartment will preferably be closed with a door 67 having a suitable lock 68.

If desired, a plate, such as shown in Fig. 8, may be mounted between the lamp 22 and the basin 19, this plate being shown at 69 90 and having an arm 70 adapted to swing about the axis of the bracket 20. By bringing this plate 69 into position over the lamp and from position under the basin, a utensil can be placed on the plate and heated. 95

What is claimed is:—

A cabinet including a body open at the front, closures for the front, and hingedly connected to opposite sides of the body, each closure being provided with supporting 100 wheels, there being a compartment within one of the closures and having an open face adapted to be closed by the body, when the closure is swung against the body, a seat hingedly mounted within said compartment, 105 another compartment within said closure and above the seat containing compartment, a drip pan constituting the bottom of the upper compartment, a vessel below and accessible through the seat, and a drain pipe 110 extending downwardly from said pan and past the seat and discharging into the vessel.

In testimony that I claim the foregoing as my own, I have hereto affixed my signature in the presence of witnesses.

ANNA V. CASSITY.
